UNITED STATES PATENT OFFICE.

FRANK E. WADE, OF FAIRMONT, MINNESOTA.

INTERNAL-COMBUSTION ENGINE.

1,142,545.

Specification of Letters Patent.

Patented June 8, 1915.

Application filed January 5, 1915. Serial No. 623.

To all whom it may concern:

Be it known that I, FRANK E. WADE, citizen of the United States, resident of Fairmont, county of Martin, State of Minnesota, have invented certain new and useful Improvements in Internal-Combustion Engines, of which the following is a specification.

My invention relates to internal combustion engines preferably of the two-cycle type, in which an auxiliary combustion chamber is provided at one end of the cylinder communicating through a port with the main combustion chamber, a by-pass being provided through which a small charge of gas is conducted to the auxiliary chamber and ignited to insure the operation of the engine at slow speed or under light load.

The object of my invention is to provide improved means for controlling the flow of gas from the by-pass into the auxiliary combustion chamber, such means being positive and reliable in action and not depending upon the use of spring or being in danger of sticking or binding in an open or closed position.

The invention consists generally in various constructions and combinations, all as hereinafter described and particularly pointed out in the claim.

Figure 1 is a longitudinal sectional view through a portion of the cylinder of a gas engine with my invention applied thereto. Fig. 2 is a transverse sectional view, showing the preferred manner of mounting the valve in the walls of the auxiliary combustion chamber.

In the drawing, 2 represents the engine cylinder and 3 the piston. The cylinder is preferably provided with a conical extension 4 at one end, forming a continuation 5 of the main combustion chamber, and at the end of this conical extension an auxiliary combustion chamber 6 is provided, said extension having a port 7 in one end leading to the chamber 6. A spark plug 8 is mounted in the side walls of said auxiliary chamber in the path of the charge of gas delivered thereto. This gas charge is conducted preferably through a by-pass 9 which extends along through the wall of the cylinder and the conical extension and around the end preferably of the auxiliary combustion chamber.

66 A plug 10 is tapped into the wall of the auxiliary chamber and a gasket 11 is pref-

erably interposed between the wall inclosing said chamber and the head 12 of the plug, said gasket preventing the water in the jacket, (not shown) inclosing the chamber 60 from working into the by-pass.

The plug 10 has a longitudinal duct 13 therein and an opening or slot 14 is provided in the side wall of the duct communicating with the by-pass, across which the plug extends, so that the charge of gas is permitted to enter the duct.

The inner end of the plug has a valve seat 15 thereon adapted to receive a ball valve 16 which has a limited movement between 70 said seat and a pin 17 that is mounted in ears 18 which project into the auxiliary combustion chamber, said pin being in the path of the ball and preventing it from falling off the seat while allowing it to drop 75 away sufficiently to permit the gas charge in the by-pass to flow into the auxiliary combustion chamber. This ball valve is free to roll around in its confined space and seat itself on the end of the plug when the charge 80 is exploded and is free to open and admit the fresh charge when the pressure is relieved in the combustion chamber. This valve having no sliding stem and being free to work around and seat itself, cannot become corroded on its seat and cannot stick as a slide valve is apt to do. Furthermore, no dependence is placed upon a spring for operating the valve, it normally opening by gravity to allow the entrance of the fresh 90 charge and closing when pressure is exerted thereon from the inside. Access to this valve may immediately be had by the removal of the plug from the wall of the 95 chamber.

I do not wish to be confined to any particular size or arrangement of this valve, as these minor details may be modified in various ways and still be within the scope 100 of my invention.

I claim as my invention:

An internal combustion engine comprising a cylinder having a main combustion chamber and an auxiliary combustion chamber at one end thereof and a port leading from said auxiliary chamber to said main chamber, said cylinder having a by-pass for the passage of gas, a plug tapped into the wall of said auxiliary combustion chamber and having a longitudinal duct therein, and an opening in the wall of said duct to communicate 105 with said by-pass when said plug is fitted 110

into the wall of said chamber, said plug having a seat at the inner end of said duct, a ball valve for said seat adapted to drop inwardly by gravity and allow the passage of
gas from said by-pass to said auxiliary chamber and means for limiting the inward movement of said valve.

In witness whereof, I have hereunto set my hand this 23rd day of December, 1914.

FRANK E. WADE.
